UNITED STATES PATENT OFFICE.

HOWELL W. HAFF, OF RICHMOND HILL, NEW YORK, ASSIGNOR TO GENERAL ACOUSTIC COMPANY, A CORPORATION OF NEW YORK.

TELEPHONE-TRANSMITTER.

No. 874,004.

Specification of Letters Patent.

Patented Dec. 17, 1907.

Application filed April 16, 1907. Serial No. 368,285.

To all whom it may concern:

Be it known that I, HOWELL W. HAFF, a citizen of the United States, residing at Richmond Hill, in the county of Queens and State 5 of New York, have invented certain new and useful Improvements in Telephone - Transmitters, of which the following is a full, clear, and exact description.

My invention relates to telephone apparatus, particularly a type of very sensitive transmitter adapted to be used with the dictograph, acousticon and other devices where a very sensitive instrument is required.

In the patent to Hyde, No. 711,974, dated 15 October 28, 1902, there is described a form of transmitter in which the sound is received around the side edges instead of against the face of a microphone instrument, and subsequently reflected so as to pass into the microphone from the rear thereof. This form of instrument is found to operate with very great efficiency in practice, the sound being collected and concentrated and in a sense brought to a focus upon the diaphragm by the reflecting 25 surfaces.

The present invention relates to improvements in the above device by which it is made still more sensitive in action. For this purpose I avail myself of the front surface or wall 30 of the microphone instrument which surface or wall has hitherto not been utilized to take advantage of the sound vibrations striking against it.

With these purposes and objects in view 35 the invention consists in the features of construction and combination hereinafter set forth and claimed.

In the drawings: Figure 1 is a front or face view of a transmitter embodying the principles of my invention; and Fig. 2 is a transverse sectional view of the same.

Referring to the drawings in which like parts are designated by the same reference sign, 1 indicates a cup-shaped body, into the 40 open front of which the sound waves are adapted to enter, the bottom or inner surface of said body being shaped to receive and concentrate the sound waves and finally direct them backward along the axis of the cup-shaped body.

3 indicates a cover or removable front portion of the body 1, and which is provided with an annular series of perforations 4 around its outside edge. The sound enters through 45 these perforations, the path thereof being in-

dicated by the dotted lines. These features are not broadly claimed in the present application as they were covered in the patent above mentioned.

The microphone or sound receiving instrument is shown at 5, and has a diaphragm 6; co-acting with the usual carbon block 7, having carbon balls 8 in cavities therein. The block 7 is supported by the plate 9 of the microphone.

11 indicates the opening of the microphone casing through which sound waves may enter to impinge against the diaphragm 6.

Any form of sound receiving device or microphone may of course be used.

The plate 9 of the microphone in accordance with the present invention is made very thin so as to be capable of vibrating in the manner of an ordinary diaphragm. The cover or front portion 3 of the body may be 70 also provided with a large opening 10, directly opposite said wall or plate 9, although this is not essential, as good results are secured if the cover 10 is left imperforate over the back of the microphone provided it is 75 made of hard rubber or resonant substance.

The important characteristic of the sound receiving device or microphone 5 is that it has, either actually or virtually, two separate diaphragms on opposite sides thereof, between which the usual microphone electrodes are included.

In use, sound waves which are directed towards the transmitter impinge against the diaphragm-wall 9 at the front and against 90 the diaphragm 6 at the rear at substantially the same instant so that pressure from both directions is applied and relieved simultaneously upon the electrodes. In this way the variations of resistance in the circuit are emphasized to a far greater degree than is the case where a single diaphragm is used, the result being a much more sensitive instrument.

What I claim, is:—

In a telephone transmitter, a cup-shaped body having openings near its edges and having its inner surface shaped to receive and concentrate sound waves therefrom, and finally direct them along the axis of the cup-shaped body, a sound receiving instrument having a cover or front portion with a large central opening through which said sound waves enter, said receiving instrument having a plate deflected at its outside edges and 110

forming part of the casing of said instrument, said plate being thin and resilient at the middle portion thereof and constituting a diaphragm, a carbon block having cavities se-
5 cured thereto, a diaphragm within said sound receiving instrument and adapted to be vibrated by the sound waves entering through said large central opening, and a plurality of carbon balls within said cavities, and estab-

lishing microphone contacts between said 10 block and said last-mentioned diaphragm.

In witness whereof, I subscribe my signature, in the presence of two witnesses.

HOWELL W. HAFF.
